UNITED STATES PATENT OFFICE.

JOHN ADT, OF NEW HAVEN, CONNECTICUT.

STAPLE-MACHINE.

SPECIFICATION forming part of Letters Patent No. 330,364, dated November 17, 1885.

Application filed April 7, 1885. Serial No. 161,463. (No model.)

To all whom it may concern:

Be it known that I, JOHN ADT, a citizen of the United States, residing at New Haven, in the county of New Haven and State of Connecticut, have invented certain new and useful Improvements in Staple-Machines, of which the following is a specification.

This invention refers to machines for making staples of that class in which the extension of the inside of each prong of the staple is beveled downward and outward to an edge, and in which a series of barbs is formed in the inside of the prongs above the said bevels.

The object of this invention is to produce the said staples rapidly and of uniform quality by the use of a style of machine generally known and understood by operators in the art of staple-making.

My invention refers specifically, therefore, to the portion of the mechanism required to form the bevels and barbs. The chief movements and arrangement of this machine up to the point of forming the bevels and barbs are substantially the same as those known to the art and used heretofore, and will therefore only require a condensed description the more clearly to distinguish the added elements of the present invention, which are to be more fully described and claimed.

30 In the drawings, Figure 1 is a side view of the blank before it is formed to a staple. Fig. 2 is a side elevation of the machine for producing the blanks and staples with the side frame removed. Fig. 3 is a top plan view of the complete machine. Fig. 4 is a vertical transverse section on line C as viewed in direction of arrow a, and Fig. 5 is a like section viewed in direction of arrow b. Fig. 6 is an enlarged transverse sectional view of dies.

40 The conditions of operation in this machine are as follows: first, to feed the wire or rods up to the stop-piece 1; second, to stop the action of the feed mechanism; third, to cut the barbs and bevels and separate the wire; fourth, 45 to bend the blank thus formed into the desired shape, whereby it becomes a staple.

The feed mechanism is not shown in the present illustration, as any one of the many well-known devices may be employed for this 50 duty.

The wire is first passed through an opening,

2, in the side frame, from whence it is caused to traverse the slot 3, formed in the fixed female die 4. This die is formed to correspond to the desired barbs and bevels, as seen, Figs. 55 5 and 6. The slot 3 is of such depth that it exactly limits the depth of the barbs to be formed in the wire, be it more or less. The traversing male die 5 is fixed to the reciprocating beam 6, and motion is transmitted to 60 the said beam and die by the cams 7 8, fast to the driving-shaft 9, which act upon the friction-rollers 10, pivotally secured to the said beam. The forms of the cams are such as to cause the die to be thrust through the wire 65 and withdrawn very quickly, and these movements are so timed relatively to the feed-motion as to take place immediately. The end of the wire impinges against the stop-piece. After the withdrawal of the male die, the 70 blank 11, Fig. 4, rests upon the cheeks 12 13, fully separated from the wire or rod at 14. The continued action of the machine will now cause one of the formers, 15, secured in the periphery of the former-wheel 16, fast to the 75 main driving-shaft 9, to strike the blank, as at arrow 17, and thus force it down between the cheeks and cause it to assume the desired form.

By reference to Fig. 6 the action of the dies 80 will be fully apprehended, and by which it will be seen that each thrust of the die finishes one end of the blank and the contiguous end of the wire, and that the long central tooth, 18, which acts to form the bevels 19, 85 Fig. 1, also effects the complete separation of the wire.

The male die is secured to the beam by the clamping-piece 20 and bolt 21, by removing which the die is free for inspection or repair. 90

As shown in the drawings, the action of the cams is such that two staples are made during each complete revolution. The metal cut from the wire is ejected from the dies and machine through the chute 22.

95 Adjustment of the die is effected by the wedge-blocks 23, adjustment of the formers by the screws 24.

It will be observed that the motion required to be given to the male die is just sufficient to 100 pass through the wire and back to permit the bending of the blank and renewed feed. This

permits rapid action without serious jar or vibration due to the reciprocating movement of the beam.

I claim—

- 5 1. In a staple-forming machine, the combination, substantially as herein set forth, of a fixed female die and a reciprocating male die, the form of the dies being such that the wire is severed and barbs are simultaneously formed in one end of the blank and the contiguous end of the wire.
- 15 2. In a staple-forming machine, the combination, substantially as herein set forth, of a fixed grooved female die, a reciprocating male die, the form of the dies being such that the wire is severed and barbs are simultaneously formed in one end of the blank and the contiguous end of the wire, and a rotary former arranged to impinge upon the blank immediately after it is severed from the wire.

3. In a staple-forming machine, the combination, substantially as herein set forth, with a fixed die, of the reciprocating beam, cams on the main shaft for propelling the same, block 20, secured to the beam, and the die 25 secured to the block by the wedge-piece.

4. In a staple-forming machine, the combination of a fixed female die and a reciprocating male die, the latter being provided with a long central tooth to sever the wire and form 30 the bevels, and having shorter teeth on each side thereof to form the barbs, substantially as herein set forth.

In testimony whereof I have signed my name to this specification in the presence of two sub- 35 scribing witnesses.

JOHN ADT.
